PLASTIC FIGURED TEXTILE FABRIC

Jerome F. Kelly, Brooklyn, N.Y., assignor to Riegel
Textile Corporation, a corporation of Delaware

Filed May 10, 1961, Ser. No. 65,100

Term of patent 14 years

(Cl. D87—3)

Fig. 1

Fig. 3

FIG. 1 is a plan view of a plastic figured textile fabric embodying my new design;

FIG. 2 is an enlarged fragmentary view of a portion of the fabric of FIG. 1; and

FIG. 3 is a cross sectional view of the fabric taken along lines 3—3 of FIG. 2.

I claim:

The ornamental design for a plastic figured textile fabric, as shown.
